GAS LAMP

Ellwood E. Little, Wichita, Kans., assignor to The Coleman Company, Inc., Wichita, Kans., a corporation of Kansas

Filed Feb. 14, 1967, Ser. No. 5,809

Term of patent 14 years

(Cl. D48—4)

FIG. 1 is a front elevational view of the gas lamp embodying my new design;

FIG. 2 is a side elevational view, the right and left sides of the lamp of FIG. 1 being identical;

FIG. 3 is a rear elevational view;

FIG. 4 is a top view; and

FIG. 5 is a bottom view.

The distinctive features of the design are characterized particularly by the showing in FIGS. 1 and 2, the lamp being normally mounted at eye-level or above with the rear side toward a wall.

I claim:

The ornamental design for a gas lamp, as shown and described.
